US0D1081040S

(12) **United States Design Patent** (10) **Patent No.:** **US D1,081,040 S**
(45) **Date of Patent:** **** Jun. 24, 2025**

(54) **ULTRASONIC DOG TRAINING DEVICE**

(71) Applicant: **Shenzhen TIZE Technology Co., Ltd,**
Shenzhen (CN)

(72) Inventor: **Jian Wen**, Shenzhen (CN)

(**) Term: **15 Years**

(21) Appl. No.: **29/947,255**

(22) Filed: **Jun. 13, 2024**

(51) LOC (15) Cl. **30-99**

(52) U.S. Cl.

USPC **D30/199; D10/104.1**

(58) **Field of Classification Search**

CLAIM

The ornamental design for an ultrasonic dog training device, as shown and described.

DESCRIPTION

FIG. 1 is a front perspective view of an ultrasonic dog training device, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the ultrasonic dog training device, which form no part of the claimed design.

1 Claim, 8 Drawing Sheets
